[57] CLAIM

The ornamental design for an amplifier for automobile, as shown and described.

DESCRIPTION

FIG. 1 is a front elevational view of an amplifier for an automobile showing my new design;

FIG. 2 is a rear elevational view;

FIG. 3 is a top plan view;

FIG. 4 is a bottom plan view;

FIG. 5 is a left side elevational view, the right side being a mirror image thereof; and

FIG. 6 is a sectional view taken along line A—A in FIG. 1, showing the location of the six small square front lights directly behind a transparent panel.
